UNITED STATES PATENT OFFICE

WILLIAM F. LISKA, OF CHICAGO, ILLINOIS

CLEANING APPARATUS

Application filed July 13, 1928. Serial No. 292,341.

This invention pertains to the general class of cleaning apparatus and particularly to a device adapted for cleaning, brushing, washing or polishing. The preferred embodiment 5 of applicant's invention such as disclosed in this application is particularly adapted for the cleaning of golf balls. However, it is understood that the device is adapted to clean, brush, scrub, wash or polish any other object 10 of suitable shape and particularly one having relatively equal dimensions irrespective of the shape or contour of the surface thereof.

An object of applicant's invention is the production of a device of this character that 15 is simple in construction, of a small number of parts, that is easily operated, that may be used to clean, brush, scrub, wash or polish as desired, that may be used with a cleaning, washing, polishing or other liquid 20 or semi-liquid substance, or even a finely divided solid substance that is so constructed that the object operated upon may be dipped into such substance, particularly when same is a liquid, that performs the operation 25 quickly and without danger of soiling the clothes, and that is highly satisfactory for its intended purpose. A further object of applicant's invention is to provide a novel method of conditioning the surface of an object or 30 objects. Many other objects and advantages of the construction herein shown and described will be obvious to those skilled in the art from the disclosure herein given.

The preferred embodiment of applicant's 35 apparatus comprises a receptacle with an open top. Positioned within said opening is a rotary member having an axis extending transversely of the receptacle. The rotary member is preferably circular and preferably 40 is covered by a housing having an opening at the top. Opposite one face of said rotary member and on an inner wall of said housing are preferably arranged spaced webs which extend downwardly into said receptacle, the 45 spaces between said webs communicating with the opening in the top of said housing. Said webs are spaced on opposite sides of the axis of said rotary member. A third web on the inner wall of said housing divides the 50 space between the first-mentioned spaced

webs. The center line of said last-mentioned web preferably intersects the axis of said rotary member. Said last-mentioned web also extends downwardly into said receptacle, however, preferably a somewhat lesser distance from the first-mentioned webs and preferably stops short of the extreme lower edge of said rotary member, such that said rotary member will carry the object operated upon below the lower edge of the intermediate web 55 from one of the channels or chutes formed by the webs to the other. When the object to be operated upon is placed in the top of one of the channels or chutes depending upon the direction of rotation of said rotary member, 60 the object is engaged by the bristles on the face of said rotary member or by any other cleaning or polishing agency or other means on the face of said rotary member. The object is carried downwardly in one channel or 65 chute, passed from one chute to the other below the bottom of the intermediate web and is returned upwardly through the other channel or chute, being brushed, scrubbed, polished or otherwise operated upon during this movement by the bristles or other agency of the 70 face of said rotary member.

To this end my invention consists in the novel construction, arrangement and combination of parts herein shown and described, 80 and more particularly pointed out in the claims.

In the drawings, wherein like reference characters indicate like or corresponding parts:

Fig. 1 is a top plan view;

Fig. 2 is a section on line 2—2 of Fig. 1;

Fig. 3 is a section on line 3—3 of Fig. 1;

and

Fig. 4 is a section on line 4—4 of Fig. 2.

Referring to the drawings, in which a preferred embodiment of the invention is shown, at 1 is a receptacle having an open top. A housing 2 having an opening 3 is attached at 4 to the upper edge of said receptacle and has a portion 5 extending downwardly into said receptacle. Mounted upon a shaft 6, extending transversely through said housing 2 is a rotary member 7. The outer end of said shaft 6 is preferably bent 95 100

or otherwise formed to provide a crank shown at 8. The rotary member 7 includes a disc 9 attached to the shaft 6. Attached to the face of the disc 9 is a brush 10 having 5 bristles 11. It is understood that any other cleaning, polishing or even abrasive means may be substituted for the brush 10. On an inner wall of housing 2 and opposite the operating face of brush 10 are webs 12, 13 and 14. In the embodiment shown, these 10 webs are arranged more or less parallel. The webs 12 and 14 are on opposite sides of the shaft 6 and are spaced therefrom. The web 13 is preferably intersected by the shaft 15. The lower edges of both webs 12 and 14 preferably extend below the lower edge of the brush 10 as clearly shown in Fig. 3. The web 13 preferably stops short of the lower edge of the brush 10 as clearly shown in 20 Fig. 3. The disc 9 is adjustable laterally of the housing 2 by means of a screw 15 which is held in place preferably by a lock nut 16. The end of the screw 15 engages a frusto-conical member 17 which engages hub 18 of 25 disc 9. The opening 3 at the top of housing 2 is preferably bounded by a rectangular or other shaped wall 19. An angular plate 20 is preferably arranged within the opening 3 in order to direct objects toward either of the 30 chutes 21 and 22 formed by the webs 12, 13 and 14. It is obvious to persons skilled in the art that grooves or other equivalent means may be substituted for the webs if desired.

35 The operation of the device is as follows: Referring to Fig. 3 it will be assumed that the brush 10 is rotating in a counterclockwise direction. The object to be cleaned shown at 23 has just been started downwardly into chute 20 so as to be engaged by the brush. When the brush is rotated counterclockwise, the object 23 will be carried downwardly in the chute 21 to the position shown at the bottom of Fig. 3 in dotted lines. The object 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285
